Inventor

UNITED STATES PATENT OFFICE.

JOHN B. LESAGE, OF MORRIS, MINNESOTA.

SLAT-REPAIRING DEVICE.

1,388,051.

Specification of Letters Patent. Patented Aug. 16, 1921.

Application filed June 4, 1920. Serial No. 386,495.

To all whom it may concern:

Be it known that I, JOHN B. LESAGE, a citizen of the United States, residing at Morris, in the county of Stevens and State of Minnesota, have invented certain new and useful Improvements in Slat-Repairing Devices, of which the following is a specification.

This invention has for its object to provide a simple and inexpensive device for facilitating the repair of broken slats on the conveyer belts or aprons of binders, although the invention is not necessarily limited to such use and is equally adaptable to repair of slats on various other aprons.

Ordinarily, slats are constructed of wood and due to their inherent fragile character are often broken. According to the present invention, such broken slats may be quickly repaired without removal from the apron by the application thereto of a repair strip suitably formed to partially embrace the broken strip and arranged to avoid contact with the flexible apron so as not to impose unnecessary wear thereof.

With these and other objects in view, the invention consists in certain novel features of construction as hereinafter shown and described and then specifically pointed out in the claim, and in the drawings illustrative of the preferred embodiment of the invention.

Figure 1 represents a fragmentary perspective view of an endless conveyer illustrating the invention applied to use thereon.

Fig. 2 represents a fragmentary longitudinal sectional view through the flexible apron of the conveyer illustrating the repairing device applied to one of the slats thereof.

Fig. 3 represents a similar transverse sectional view through a slat illustrating the manner of repairing the latter subsequent to its removal from the apron.

Fig. 4 represents an enlarged fragmentary perspective view of a broken slat illustrating the repairing device applied thereto, and,

Fig. 5 represents an enlarged plan view of the blank from which the device is constructed.

Referring to the drawing in detail, wherein similar reference numerals designate corresponding parts throughout the several views, there is illustrated an elongated blank 5 of flat sheet metal forming the body

the repair device which is preferably constructed of metal of suitable thickness to lend requisite strength and rigidity to the device when applied to use. The blank is folded along two spaced longitudinal lines 60 indicated by the dotted lines 6 in Fig. 5, the lines of fold being separated a distance approximately equal to the width of the slat 7 to which the device is designed for application.

By turning the portions of the blank laterally along the lines 6, retaining flanges 8 are provided which embrace the opposite side edges of the slat 7 and effectively maintain the broken terminals thereof in proper alignment. The body or that portion of the device lying intermediate the flanges 8 is formed on opposite sides of the longitudinal center of the blank with a plurality of apertures 9 adapted to receive rivets or equivalent fastening elements 10 which are also passed through the slat thereby retaining the repair device in position thereon and preventing relative movement of the broken pieces of the slat.

In conventional types of conveyers for binders and similar machines, the apron 11 is constructed of fabric or other material having proper flexible qualities and in order to prevent such wear as would be incurred 85 by frictional contact of the edges of the flanges 8 with the fabric of the apron, said flanges are preferably of less width than the thickness of the strip 7 to which the repair device is applied. In this manner, the 90 edges of the repair device are maintained in spaced relation to the apron thereby eliminating wear.

In use, when a slat of the apron is broken at any point intermediate its ends, the repair device is so applied that the adjacent ends of the broken pieces of the slat are embraced by the body and flanges 8. The rivets 10 are subsequently inserted through the apertures 9 in the body of the repair device 100 and through registering apertures formed in the broken pieces of the slat 7. By subsequently upsetting the terminals of the rivets the broken pieces of the slat are permanently and rigidly connected. If preferred, the rivets 10 may be extended entirely through the apron 11 or, if preferred, the broken pieces of the slat may be removed from the apron and the repair device applied to the broken pieces of the slat 110

independently of the apron, as suggested in Fig. 3 and the slat subsequently reapplied to the apron.

The preferred embodiment of the invention is disclosed in the drawings and set forth in the specification, but it will be understood that any modifications within the scope of the claim may be made in the construction without departing from the principle of the invention or sacrificing any of its advantages.

What I claim is:

As an article of manufacture, a repair device for broken wooden slats of endless conveyer aprons comprising a substantially elongated body of sheet metal formed to provide oppositely depending side flanges adapted to embrace the opposite sides of

the broken pieces of the slat, the flanges being of less width than the thickness of the slats, whereby to provide a space between the edges of the flanges and the apron of the conveyer and thereby prevent contact of the edges of the flanges with the apron during the travel of the latter, the connected portion of the body being provided with sets of spaced apertures disposed on the longitudinal center thereof, one set to each side of the transverse center of the same, whereby the fastening devices used may be properly inserted through the body with respect to the line of the break between the parts of the broken slat.

In testimony whereof, I affix my signature hereto.

JOHN B. LESAGE.
